UNITED STATES PATENT OFFICE.

FRANK L. WRIGHT, OF CHICAGO, ILLINOIS, ASSIGNOR TO THE LUXFER PRISM PATENTS COMPANY, OF SAME PLACE.

DESIGN FOR A PRISM-PLATE.

SPECIFICATION forming part of Design No. 27,998, dated December 7, 1897.

Application filed October 23, 1897. Serial No. 656,226. Term of patent 14 years.

To all whom it may concern:

Be it known that I, FRANK L. WRIGHT, a citizen of the United States, residing at Chicago, in the county of Cook and State of Illinois, have invented a certain new and original Design for Prism-Plates, of which the following is a description.

My invention relates to designs for prism-plates.

Figure 1 is a plan view of a prism-plate embodying my design. Fig. 2 is a section there-through.

A is the body of the prism-plate.

B B are a series of surface areas substantially uniform in appearance and produced by the lines of separation C C, which cross the surface of the body of the plate. D D are prisms on the opposite side.

Upon the surface of the prism-plate and intermediate between its center and outer edge

a group of areas forming an annulus are ornamented by means of the lines E E. These lines are produced on the surface of the prism-plate.

The essential features of my design are found in a prism-plate consisting of a substantially flat body with a series of prisms on one side and lines of separation on the other, which divide the surface into a series of substantially uniform surface areas, and an annulus formed on the surface intermediate between the center and the outer edge by means of lines of ornamentation.

I claim—

A design for a prism-plate, substantially as shown and described.

FRANK L. WRIGHT.
